UNITED STATES PATENT OFFICE.

JAMES E. ALLISON, OF ST. LOUIS, MISSOURI, ASSIGNOR TO THE LACLEDE MANUFACTURING COMPANY, OF ST. LOUIS, MISSOURI, A CORPORATION OF MISSOURI.

COIN-CONTROLLED VENDING-MACHINE.

No. 899,198.

Specification of Letters Patent.

Patented Sept. 22, 1908.

Application filed December 29, 1905. Serial No. 293,789.

To all whom it may concern:

Be it known that I, JAMES E. ALLISON, a citizen of the United States, residing at St. Louis, Missouri, have invented a certain new and useful Improvement in Coin-Controlled Vending-Machines, of which the following is a full, clear, and exact description, such as will enable others skilled in the art to which it appertains to make and use the same, reference being had to the accompanying drawings, forming part of this specification, in which—

Figure 1 is a vertical sectional view through my improved coin-controlled vending machine; Fig. 2 is a sectional view on the line 2—2 of Fig. 1; Fig. 3 is a similar view showing the parts in a changed position; and Fig. 4 is a similar view showing the parts in still another position.

This invention relates to a new and useful improvement in coin-controlled vending machines, the object being to simplify the construction of devices of this character whereby the number of parts entering into the mechanism are comparatively few, the cost of construction and liability to get out of order are reduced to a minimum.

With these objects in view, the invention consists in the construction, arrangement and combination of the several parts, all as will be hereinafter described and afterwards pointed out in the claims.

In the drawings, 1 indicates the base preferably in the form of a casting, the bottom of which is closed by a plate 2 forming a coin receptacle. The upper part of the base is provided with a circular flange 3 which is cut away at its front side to expose a portion of a rotary member 4 in the form of a turn-table. This rotary member 4 is mounted on the upper end of a stud shaft 5 arranged in a part of the base casting, a torsional spring 6 being employed to hold the turn-table 4 in its home position. The web 1^a of the base casting which supports the hub in which the stud shaft is mounted is cut away at 1^b to form a concentric coin slot.

Referring to Fig. 1, it will be seen that the turn-table 4 is provided with a depending flange 4^a fitting within the concentric flange 3, said depending flange 4^a being provided with notches 4^b in the form of ratchet teeth on its inner periphery, as shown in Figs. 2, 3 and 4. 4^c indicates a coin slot in the turn-table, which coin slot is in the vertical plane

of the ratchet teeth 4^b, whereby when a coin is inserted into said slot said coin drops into a position in front of said teeth and constitutes a guard to prevent engagement of the pawl 7 with said ratchet teeth.

Referring to Fig. 2, which illustrates the normal position of the parts, it will be seen that the pawl 7 rests upon the smooth surface of the flange 4^a which constitutes a track for the pawl and over which the stationary mounted pawl 7 rides when the turn-table is rotated. Should the handle 4^d of the turn table be grasped and the turn-table moved in the direction of the arrow in Fig. 2, the absence of a coin which would serve as a guard for the ratchet teeth would permit the pawl 7 to engage the ratchet teeth and prevent more than a slight movement of the turn-table. When the handle is released the turn-table will be restored to its normal position by the spring 6. However, when a coin is inserted in the slot 4^c said coin will drop in front of the ratchet teeth 4^b and form a continuation of the pawl track, and when the turn-table is rotated in the direction of the arrow in Fig. 2 the pawl 7 will ride over the coin, permitting a complete movement of the turn-table, which complete movement locates the coin over the opening 1^b through which opening the coin will drop into the coin receptacle.

The upper surface of the turn table is provided with two parallel flanges 4^e, the space therebetween acting as a recess into which the packages X to be vended drop by gravity. The depth of the recess is substantially the depth of the package X. The packages X are oblong in shape and when the turn-table is in its home position the recess between the flanges extends in a direction parallel to the long axis of the package, and in this manner the packages drop one by one into the recess as the packages are successively removed therefrom. When a coin is dropped into the slot and the turn-table is rotated the package contained in the recess will be carried with the turn-table and the flanges constituting the recess will move into position under the next adjacent package supporting the same and the superposed packages.

9 indicates an arm pivotally mounted upon the base casting 1 and having a tappet 9^a which is designed to be struck by one of the flanges 4^e when the turn-table is rotated and swing the arm 9 over the surface of the turn-

table into the space between the flanges so as to force the package outwardly. This arm 9 constitutes an ejecting mechanism and enables the operator to readily grasp the projecting end of the package and remove the same from the recess when, upon the release of the handle, the turn-table will be restored to its normal position in readiness for another operation. The return of the turn-table to 10 normal position causes the flange 4^e which operated the tappet 9^a to engage the arm 9 and move the same back out of the recess so as to permit another package to drop into the recess. Extending up from the base 1 is a 15 casing 10, the front panel 11 of which is preferably of glass so as to give a view of the packages contained in the casing, while the panel 12 slides vertically in ways so as to give access to the interior of the casing. The upper 20 end of panel 12 is bent inwardly over a perforated lug 13 on the cap piece of the casing through which, when the panel 12 is down, may be passed a lock to prevent access to the interior of the casing by a person not 25 possessing a key to the lock. The casing is substantially rectangular in cross section and of such type as to enable the desired number of packages to be arranged therein, the rectangular form of the casing holding the packages 30 against rotation and in proper position to coöperate with the recess in the turn-table.

I am aware that minor changes in the construction, arrangement and combination of the several parts of my device can be made 35 and substituted for those herein shown and described without in the least departing from the nature and principle of my invention.

Having thus described the invention, what is claimed as new and desired to be secured 40 by Letters Patent is:

1. In a coin-controlled vending machine,

the combination of a turn-table, provided with a depending flange constituting a pawl track, teeth on the inner face of said track, a stationarily-mounted restraining pawl riding 45 upon said track and coöoperating with said teeth to prevent movement of said turn-table in the absence of a coin, and means for supporting a coin in position in front of said teeth to prevent engagement of the pawl 50 therewith; substantially as described.

2. In a coin-controlled vending machine, the combination of a turn-table having a delivery recess, a track on said turn-table, a 55 pawl coöperating with said track, teeth in said track with which said pawl is adapted to engage to prevent complete movement of said turn-table, said table being provided with a coin-receiving slot, and means for supporting a coin in front of said teeth to prevent 60 engagement of the pawl with the teeth; substantially as described.

3. In a coin-controlled vending machine, the combination with a turn-table having a delivery recess, a pawl track on said turn-table, teeth in said pawl track, a pawl adapted to coöperate with said track and said teeth, said table being provided with a coin-receiving recess for delivering a coin opposite said teeth, a support for holding the coin in position opposite the teeth, and means whereby when the turn-table is rotated the coin will be dislodged from its position and the turn-table completes its movement; substantially 70 as described.

In testimony whereof, I hereunto affix my signature, in the presence of two witnesses, this 26th day of December 1905.

JAMES E. ALLISON.
